UNITED STATES PATENT OFFICE.

JOHN L. DALE, OF WHALEYSVILLE, MARYLAND.

LATCH.

SPECIFICATION forming part of Letters Patent No. 505,033, dated September 12, 1893.

Application filed April 5, 1893. Serial No. 469,170. (No model.)

To all whom it may concern:

Be it known that I, JOHN L. DALE, of Whaleyville, in the county of Worcester and State of Maryland, have invented a new and useful Improvement in Door-Latches, of which the following is a specification.

My invention is an improvement in latches for use on doors, gates and the like and the invention consists in the novel constructions, combinations and arrangements of parts as will be hereinafter described and pointed out in the claim.

In the drawings—Figure 1 is a face view of my latch as in use, it being shown fastened in full lines and released in dotted lines. Fig. 2 is a detail view of the catch. Fig. 3 is a detail view of the latch bar. Fig. 4 is a detail view of the keeper and Fig. 5 shows another form of catch.

20 The door or gate A and the frame or case B into which it closes may be of any ordinary construction the catch C being in operation supported on the frame or case and the latch D on the door.

25 In practice the latch may be arranged to cross the edge of the door at an incline as shown or it may be arranged at right angles thereto without departing from the improvement. The catch is formed with the under-
30 cut notch or notches C' forming locking seats for the latch bar. It is preferred to form these notches in the opposite sides of the catch as shown. In securing the catch it may have a base plate C³ held by screws firmly to the
35 frame as shown in Fig. 1 or it may be provided with a screw shank as shown in Fig. 5

to screw into the frame. The latch D comprises the spring rod or bar E provided at its outer end where it engages the catch with the handle e and the clip F in which the opposite 40 or inner end of the rod E is held.

In connecting the clip and latch rod it is preferred to provide the inner end of said rod with a short lateral projection or stud e' entering an opening or seat f' in the arched 45 portion f of the clip. This construction is simple, cheaply effected in manufacturing the latch and operates efficiently to prevent any longitudinal or turning motion of the latch and the rod is usually soldered or otherwise 50 fastened in the clip plate to hold the clip and rod together until the latch is applied for use. The clip has lateral flange plates F' perforated for the screws which secure it in place.

In manufacturing the latch it may be en- 55 amealed, nickelized or otherwise ornamented, and may be made of steel, brass or other suitable metal.

Having thus described my invention, what I claim as new, and desire to secure by Letters 60 Patent, is—

A latch comprising a clip having an arched portion provided with an opening or seat, and the rod fitted at one end to said arched portion and having a lateral portion or stud to 65 enter said opening or seat substantially as and for the purposes set forth.

JNO. L. DALE.
